(57) **CLAIM**

The ornamental design for a furniture panel pattern, as shown and described.

DESCRIPTION

FIG. 1 is a front perspective view of furniture panel pattern showing my new design, illustrating the furniture panel pattern at a two-drawer furniture.

FIG. 2 is a front view thereof, illustrating the furniture panel pattern at the two-drawer furniture.

FIG. 3 is a front perspective view of furniture panel pattern showing my new design, illustrating the furniture panel pattern at a four-drawer furniture.

FIG. 4 is a front view thereof, illustrating the furniture panel pattern at the four-drawer furniture.

FIG. 5 is a front perspective view of furniture panel pattern showing my new design, illustrating the furniture panel pattern at a three-drawer furniture; and,

FIG. 6 is a front view thereof, illustrating the furniture panel pattern at the three-drawer furniture.

The broken lines in FIGS. 1 to 6 of the drawings are for illustrative purposes only and form no part of the claimed design.
